UNITED STATES PATENT OFFICE

IRVEN H. WILSEY, OF CHICAGO, ILLINOIS, ASSIGNOR OF ONE-HALF TO JAMES B. TUT-
HILL, OF CHICAGO, ILLINOIS

BRICK LIFTING AND TRANSFERRING MECHANISM

Application filed January 5, 1927. Serial No. 159,043.

The present invention relates to improvements in a brick-lifting and transferring mechanism, and particularly a mechanism for handling a large stack of bricks as a unit.

5 Mechanisms of the above character are commonly provided with a plurality of parallel spaced lifting arms or prongs, which are adapted to be inserted into spaces between bricks in the basic layers of the stack, and 10 which have clamping means for engaging the bricks in said layers so as to constitute the latter and the arms a support for the entire stack.

The primary object of the present invention resides in the provision in such mechanism of novel clamping means which are hydraulically actuated so as to obtain elasticity and a uniform clamping pressure.

A further object is to provide a brick-20 handling device or fork which is extremely simple in construction, and does not comprise a complicated system of levers, links, and springs, as is common in many prior art constructions, for actuating the clamping 25 means, which is inexpensive in construction, and which is easy and quick to manipulate.

Still another object is to provide a new and improved brick-handling fork which is responsive and efficient in operation, and which 30 is adapted to exert a strong and secure clamping effect on one or more of the basic layers of a stack of bricks.

Specific objects of the invention reside in the specific clamping devices on the lifting 35 arms.

Ancillary objects and advantages will become apparent as the description proceeds.

In the accompanying drawings, in which I have illustrated the preferred embodiment 40 of my invention, Figure 1 is an end elevation of the brick fork.

Fig. 2 is a plan view.

Fig. 3 is an enlarged fragmentary side 45 view of one end of one of the supporting arms or prongs.

Fig. 4 is a transverse sectional view through a pair of arms, taken along line 4-4 of Fig. 3.

50 Fig. 5 is a transverse sectional view

through a pair of arms, taken along line 5-5 of Fig. 3.

While the invention is susceptible of various modifications and alternative constructions, I have shown in the drawings and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

Referring to the drawings, the exemplary embodiment of the invention comprises a frame which may have any suitable form, and which in the present instance consists of a vertical webbed plate or frame member 10. A pair of spaced horizontal arms 11 are secured transversely to the upper edge of the member 10, and preferably are formed integral therewith. These arms extend mainly to one side of the member 10, and are adapted to be connected to a suitable supporting means (not shown).

Projecting laterally from the lower edge of the frame member 10, and underlying the arms 11, are a plurality of spaced parallel lifting arms, bars or prongs 12. These bars 12 preferably are formed in an integral fork-like structure 13 secured to the frame member 10 by any suitable means, such as the bolts 14. To facilitate insertion of the fork 13 into suitable spaces between bricks in the basic layers of a stack, each bar 12 is relatively narrow and is pointed at its free end, as indicated at 15. In Figs. 4 and 5, I have shown part of the two basic layers 16 and 17 of a stack of bricks. The full

second basic layer 17 is shown in Fig. 2. The bricks in each layer are arranged in rows 18 of two, separated by spaces 19. One side of each lifting bar 12 is provided with a smooth surface against which one row 18 of the lower basic layers 16 and 17 is adapted to be clamped. The other side of each bar 12 is provided with a plurality of clamping devices. While the basic layer 16 alone of the stack may be clamped to the bars 12, preferably the two basic layers 16 and 17

are so clamped, and hence two sets of clamping devices are provided.

Each of the clamping devices for the second basic layer 17 of bricks (see Fig. 4) comprises a clamping dog or plate 20 which is pivoted at its upper end on a pin 21 between a pair of lugs 22. These lugs are fixed to the inner wall of a recess 23 in one side of the lifting bar. The pivoted end of the clamping dog 20 is bifurcated. A spring 24 tends to hold the dog 20 within the recess 23 and out of clamping engagement with the layer 17. The upper end of a link 25 is pivotally secured to the clamping dog 20 and 15 between the bifurcated arms thereof. The lower end of the actuating link 25 is pivotally connected to a pair of spaced lugs 26 formed on the closed end of a movable cylinder 27. This cylinder is slidably mounted 20 on a stationary piston 28 rigidly mounted in the lower end of the recess 23. Pressure fluid, such as compressed air, is adapted to be admitted to the cylinder 27 through a central axial bore 29 in the piston, said bore 25 being connected to an air duct or passage 30 formed in the lifting bar. The air duct 30 is connected to a suitable air supply line 31 provided with a suitable control valve (not shown). It will be evident that the clamping dog 20 constitutes a third-class lever, and that the bifurcated arms of the dog and the 30 link 25 constitute a toggle for moving the end of the dog outwardly into clamping engagement with the adjacent side of the brick 35 when pressure fluid is admitted to the cylinder 27.

Each of the clamping devices for the first basic layer 16 of bricks (see Fig. 5) comprises a clamping dog or plate 32 having an upper bifurcated end. The dog 32 is pivoted intermediate its ends on a pin 33 between two lugs 34. These lugs are mounted beside the cylinder 27 in the recess 23. A spring 35, preferably coiled on the pivot pin 33 and 40 respectively engaging the lifting bar 12 and the dog 32 at its opposite ends, tends to yieldingly retain the dog within the recess 23 and out of clamping engagement with the brick. The bifurcated end of the clamping dog 32 is pivoted to the lower end of a vertical link 36. The upper end of the link 36 extends into an axial bore 37 in the lower end of a piston 38, and is therein pivotally connected to the piston. The latter is reciprocable in 45 a vertical cylinder 39 formed in the lifting bar 12, and communicating directly with the air supply duct 30. It will be evident that the clamping dog 32, constitutes a first-class lever movable outwardly into clamping engagement with the brick when pressure fluid is admitted to the cylinder 39.

In operation, the lifting bars 12 are moved into the spaces 19. Pressure fluid, such as compressed air, is then supplied to the duct 43 30. The compressed air enters the cylinders

27, and raises the latter to force the clamping dogs 20 outwardly and upwardly into engagement with the rows 18 of the second layer 17 of the stack, thereby clamping said rows securely against the smooth sides of the lifting bars 12. Pressure fluid also enters the cylinders 39 and forces the pistons 38 downwardly, thereby moving the clamping dogs 32 outwardly into clamping engagement with the rows 18 of the first layer 16 of the brick stack. The lifting bars 12 and the clamped layers 16 and 17 of brick constitute a suitable supporting base for the remainder of the stack, and the latter can therefore be lifted and transported as a single unit from place to place. 75 80

It will be evident that I have provided a brick-lifting and transferring mechanism, conveniently designated as a brick fork, which is simple and inexpensive in construction, by which the basic layers of a brick stack are clamped uniformly through the medium of a flexible clamping force, thereby compensating for irregularities in the surface of the brick, and which is efficient in operation. 85

I claim as my invention:

1. A brick fork having, in combination, a pair of lifting bars, a series of recesses formed in one side of one bar, a series of clamping dogs pivotally mounted in said recesses for clamping the upper layer of two layers of brick against the adjacent side of the other bar, a series of clamping dogs pivotally mounted in said recesses for clamping the lower layer of said two layers of brick against the adjacent side of said other bar, a plurality of piston and cylinder units, one for each clamping dog, means operatively connecting the movable member of each piston and cylinder unit to the associated dog, and means for supplying fluid pressure to said piston and cylinder units. 95 100 105

2. A brick fork having, in combination, a frame, a plurality of parallel spaced lifting bars mounted on said frame, one side of each bar presenting a smooth clamping surface, a plurality of clamping plates movably mounted in the other side of each bar and adapted to clamp brick against said surface, a plurality of piston and cylinder units operatively connected respectively to said clamping plates for actuating the latter, and ducts formed in said bars and opening to said units for supplying fluid pressure to said units. 110 115 120

3. A brick fork having, in combination, a frame, a plurality of parallel spaced lifting bars on said frame, a plurality of clamping dogs movably mounted in said bars, spring means tending to hold said clamping dogs in inoperative position, a plurality of piston and cylinder units one operatively connected to each of said dogs for moving the latter into clamping engagement with brick between said bars, and means for supplying 125 130

fluid pressure to said piston and cylinder units.

4. A brick fork having, in combination, a frame, a plurality of parallel lifting bars mounted on said frame and adapted to be inserted into spaces between the brick of the two basic layers of a stack, a series of clamping devices arranged on said bars to engage the first basic layer of the stack, a series of 10 clamping devices arranged on said bars to engage the second basic layer of said stack, a plurality of independent fluid pressure responsive means for actuating said clamping devices, and means for directing fluid pressure to said first mentioned means.

5. In a brick fork, in combination, a lifting bar, a clamping member pivotally mounted on said bar, a piston and cylinder unit one member of which is fixed to 20 said bar and the other member of which is movable, a link connecting said movable member to said clamping member, and a fluid pressure supply passage opening into the cylinder of said unit.

25 6. In a brick fork, in combination, a horizontal lifting bar, a pair of vertically spaced clamping members mounted on said bar for movement laterally thereof, a plurality of spaced piston and cylinder units, the movable elements of said units being operatively connected respectively to said members, said bar being formed with a duct communicating with said units for directing pressure fluid thereto to urge said members outwardly from 30 said bar, and spring means tending to urge said members inwardly toward said bar.

In testimony whereof, I have hereunto affixed my signature.

IRVEN H. WILSEY.
